UNITED STATES PATENT OFFICE.

THOMAS PETER EUSTEDE, OF WELLINGTON, NEW ZEALAND.

WINDOW STAY AND FASTENER.

1,410,902.

Specification of Letters Patent. Patented Mar. 28, 1922.

Application filed September 9, 1920. Serial No. 409,263.

To all whom it may concern:

Be it known that I, THOMAS PETER EUSTEDE, a subject of the King of Great Britain and Ireland, residing in Hataitai, 5 Wellington, New Zealand, have invented a new and useful Improvement in Window Stays and Fasteners; and I do hereby declare the following to be a full, clear, and exact description of the same.

10 This invention relates to that class of casement window fastener in which a stay member slides upon a rod and assumes a position parallel or nearly parallel with the rod when the sash is closed.

15 The chief object of the present invention is to provide a fastener in which the stay forms a locking device when the sash is closed.

In the present invention the stay member 20 is arranged so that when the sash is closed the end of the member connected to the sash will lock into a bracket upon the frame or a sliding plate upon the stay member will form a locking member. The stay member 25 is pivotally connected to the sash of the window at one end while the other end is slideable upon a rod fixed to the frame, or the arrangement may be that the stay slides upon a rod fixed to the sash.

30 The invention is illustrated in the accompanying drawings, wherein:—

Figure 1, is a view showing the fastener applied to a casement window.

Figure 2, is a front view of the device in 35 position on a window frame.

Figure 3, is a side elevation thereof.

Figure 4, is a side elevation showing a position of the stay when the window is partly open.

40 Figure 5, is a plan of a bracket.

Figure 6, is a front view, and

Figure 7, is a side view of an alternate locking member.

Figure 8, is a front elevation of an extensible stay.

Figure 9, is a plan of a bracket.

Figure 10, is a sectional plan of a detail on line B—B, Figure 8.

Figure 11, is a plan of a bracket.

50 Figure 12, is a plan of a stay particularly adapted for use upon the sill of a window.

Figure 13, is a front view showing the device in a closed position.

55 Figure 14, is a plan view, and

Figure 15, is a front view of the locking portion of an alternate construction.

On the drawings the same reference numerals indicate the same parts in the different views.

Referring first to Figures 2 to 7, the fastener comprises a stay member 1 pivoted to the sash 2 of a window by means of a universal joint consisting of a bracket 3 in which is pivoted another bracket 4 on a pin 5, the stay member 1 being connected to the bracket 4 by a pin 6 passing through the lugs thereof. The other end of the stay member 1 has a slot 7 in which slides a pin 8 the head 9 of which slides upon a vertical rod 10 secured in brackets 11 and 12 fixed to the window frame 13. The pin 8 has a knob 14 threaded thereon, the knob being prevented from unscrewing from the pin by means of a washer 15 riveted upon the end of the pin. The pin 8 passes through a U shaped shoe 16 also sliding upon the rod 10. By tightening the rod 14 the shoe forces together the rod 10 and the stay member 1 so as to hold them rigidly together. A plate 17 is slidably mounted upon the lower end of the stay member 1 by means of pins or rivets 18 or 19, the latter forming an operating knob. These pins pass through a slot 20 in the stay member 1 and, if desired, a coil spring 21 may be attached at one end to the pin 18 and at the other end to the stay member 1 and located in the slot 20 so as to retain the plate in its normal position. The lower end of the plate 20 has its front edge slightly bevelled at 22 and its rear edge bevelled at 23 as shown and is adapted to enter a slot 24 in the bracket 12.

In Figures 6 and 7, the pin 5 is made longer than that shown in Figures 2 and 3, and in place of the sliding plate 17 a plate 26 is fixed to the stay. The bracket 4 slides on the pin 5 and so permits of vertical movement of the stay 1 to ride over the bracket 12 and to be disengaged therefrom. The end of the plate 26 is adapted to enter the slot 27 in the bracket 12.

The operation is as follows:—

Assuming the window to be open and the stay in the position shown in Figure 4 and it is desired to close the window, the knob 14 is slackened and the sash closed. At the same time the operator permits the pin 9 to slide upwards upon the rod 10 until the bevelled edge 23 upon the plate 17 contacts

with the bevelled edge 28 upon the bracket 12, and the plate will ride over the bracket 12 and drop into the slot 24.

In the type shown in Figures 2 and 4, the 5 weight of the plate will be sufficient to cause it to enter the slot and, if desired, the spring 21 may be introduced to make the action more certain, while in the type shown in Figures 6 and 7 the whole weight of the stay 10 and accompanying parts will make the action certain, but if desired the spring 21 may be introduced around the pin 5 as shown.

To complete the locking, the operator may force the plate 17 or 26, as the case may be, 15 downwardly by means of the knob 19, the bevelled edge 22 tending to draw the sash against the frame. In order to make the fastening more secure he may tighten the knob 14. By the shape of the locking plate 20 any looseness of the sash will only tend to let the plate fall lower and further tighten the window.

To open the sash, the knob 14 is slackened and the plate 17 or the plate 27 disengaged 25 by operating the knob 19 and the sash secured in the desired open position by tightening the knob 14. The slot 7 permits of further adjustment of the stay when the pin 9 is at the bottom of the rod 10, as indicated in Figure 1.

Referring now to Figures 8 to 11, the stay is made in the same way except that an extension rod 30 is provided and is fixed at its upper end in a guide 31 slidable upon the 35 stay 1. Another adjusting knob 32 is threaded upon a pin having a head 33 and a shoe 34 slidable on the extension bar 30, these parts being of the same construction as those shown in Figure 10. In this case, 40 the extension member 30 is pivoted to a bracket 4 and when the sash is closed a cut-away portion 35 in the bracket 12 permits the stay to assume a closed position. The lower end of the stay member 1 is provided 45 with the bevelled portions 22 and 23 and is adapted to enter a slot 36 in the bracket 12.

The bracket 11 has a slot 37 into which the upper end of the stay member 1 enters when closing in order to form a guide to retain the member 1 in position to ride over the plate 12 and ensure it entering the slot 36.

Figure 1, shows this type of fastener in position the extension bar 30 being shown partially extended. The operation is the 55 same as in regard to types in the previous figures, with the exception that the adjusting knob 32 must also be operated when opening or closing the sash.

Although the device has been illustrated 60 as applied in a vertical position upon the window frame, it is obvious that any of the devices may be employed upon the sill of the window frame. In such a case the rod 10 would be fixed horizontally on the sill 65 and instead of the universal joint the end

of the stay member would be pivoted to a bracket fixed to the bottom rail of the sash.

In Figures 12 and 13 is shown a type of stay particularly adapted for use upon the sill of the window frame, and in which the 70 parts that are the same in the previous figures have the same reference numbers. In place of the stay being pivoted in the brackets 3 it is pivoted upon a pin 38 sliding upon a rod 39 fixed in brackets 40 secured to the 75 bottom rail of the sash. This arrangement permits of the sash being opened and secured rigidly at almost any angle by means of a comparatively short stay. Such an opening is shown in Figure 12 and by adjusting 80 the stay to any position upon the rod 39 and the other end along the rod 10, any degree of opening may be obtained. The two rods 10 and 39 permit of the stay being placed at an angle in relation to either rod that will 85 give the maximum rigidity.

A slot 41 in the end of the stay permits the stay to slide backwards sufficiently so that when the bevelled edge 23 contacts with the bracket 12 the stay will clear the bracket. 90 The end of the stay is then simply inserted into the slot 24 by means of the knob 42 being operated in the direction of the arrow in Figure 13.

In Figures 14 and 15 the stay is shown 95 pivoted on a pin 43 projecting from a bracket 44 which is fixed to the sill of the window, while the other end slides upon a rod 39. In this case, a locking plate 45 is guided upon the pin 38 and upon a pin 46. 100 A lip 47 on the end of the plate permits of the plate being operated.

What I claim is:—

1. The combination with a window frame and sash therefor, of a stay member having one end connected to the window frame, the opposite end of said stay member being connected to the sash, and a member mounted on the window frame, said member being provided with a slot adapted to receive a portion of the stay member when the sash is in closed position.

2. A window stay and fastener comprising a support, a stay member slidably connected thereto, said connection being provided with means for retaining the stay member in adjusted positions and means carried by said support adapted to engage the opposite end of the stay member when the stay member is in one position.

3. In a window stay and fastener comprising supporting brackets, a rod mounted therein, a stay member having one end pivotally and adjustably connected to said rod, and means carried by said stay member whereby its opposite end may be retained in locking engagement with one of said supporting brackets.

4. In a window stay and fastener comprising a support, a rod mounted thereupon, an

adjustable stay member pivotally connected to said rod, a latch member carried by said stay member and means whereby said latch member may retain said stay member in locking engagement with said support.

5. The combination with a window frame and a sash therefor, of brackets mounted upon said frame, a rod supported by said brackets, a stay member adjustably connected to said rod, means for pivotally connecting said stay member to the window and a spring actuated latch member carried by said stay member whereby the sash may be retained in closed position within the window frame.

6. The combination with a window frame and a sash therefor, of a support carried by the window frame, a rod mounted upon said support, a stay member having one end 20 pivotally and adjustably connected to said rod, a bracket carried by the window sash, the opposite end of said member being pivotally connected to said bracket, a slidable latch member connected to said stay member and adapted to engage said support, and a knob for manually releasing said latch member.

7. In a window stay and fastener, a rod fixed to the window frame, a stay member 30 sliding upon said rod, means for adjusting said stay member in different positions upon said rod, one end of said stay being pivotally connected to the window sash, a bracket fixed to the window frame, and a latch on the end of the stay member that is connected to the window sash whereby during the closing movement of said sash said latch member will automatically lock into said bracket.

40 8. In a window stay and fastener, a stay member, a rod fixed to the frame of the window upon which slides said stay member, means whereby said stay member may

be adjusted to different positions on said rod, one end of said stay member being 45 pivotally connected to the window sash, a bracket fixed to the window frame, and means whereby when a limited amount of sliding movement is given to said stay member it will automatically engage and lock 50 into said bracket.

9. In a window stay and fastener, a rod fixed to the window frame, a stay member sliding upon said rod, means for adjusting said stay member to different positions upon 55 said rod, one end of said stay member being pivotally connected to the window sash, a bracket fixed to the window frame, means arranged adjacent the end of the stay member that is connected to the window sash to 60 lock into said bracket, a pin mounted upon said sash, a slidable bracket mounted upon said pin and one end of said stay member being pivotally connected to said slidable bracket.

65 10. In a window stay and fastener comprising a stay member, means for connecting one end of said stay member to the window frame, a bracket carried by said window frame, a spring actuated sleeve slidably 70 connected to the window sash, means for pivotally connecting said stay member to said sleeve, means whereby said stay member may engage said bracket for retaining said window sash in closed position and 75 means for manually moving said stay member whereby it may be engaged from said bracket and said sash permitted to be opened.

In testimony whereof, I have signed my 80 name to this specification in the presence of two subscribing witnesses.

THOS. PETER EUSTEGE.
